Inventor:

Hiram Holden,

by *Frank Middleton, Jonathan Peas.* Atty's.

UNITED STATES PATENT OFFICE.

HIRAM HOLDEN, OF MANCHESTER, NEW HAMPSHIRE.

SHOE.

1,193,688.

Specification of Letters Patent.

Patented Aug. 8, 1916.

Application filed March 20, 1916. Serial No. 85,502.

To all whom it may concern:

Be it known that I, HIRAM HOLDEN, a citizen of the United States, residing at Manchester, New Hampshire, have invented certain new and useful Improvements in Shoes, of which the following is a specification.

My present invention relates to improvements in the manufacture of boots and shoes and pertains more particularly to the provision of an improved border strip which may be used in different places in the construction of shoes to augment the leather and increase the working area of the material without in any way weakening or marring the appearance of the finished shoe.

An improved marginal strip of this general design and purpose is disclosed in my co-pending application, Serial No. 64,741, allowed January 20th, 1916, of which this present invention is an improvement. The purpose of this marginal strip is to afford an increased area and a strengthened working edge, thus minimizing the amount of expensive leather needed.

A further object of the invention consists in providing such a form of marginal strip as will be inexpensive to make and will possess the necessary strength and wear resisting qualities.

With these and other objects in view the invention consists in the combination and arrangement of parts hereinafter more fully set forth in the following specification, illustrated in the accompanying drawing and pointed out in the claims.

In the drawing: Figure 1 shows a portion of an upper with one embodiment of the present invention attached thereto. Fig. 2 is a transverse sectional view of a partially completed welted shoe, which includes an upper construction as shown by Fig. 1. Fig. 3 is a fragmentary plan view of the marginal strip and stitching attached to the edge of the leather. Fig. 4 is an enlarged detail edge view showing the form of stitching used.

In Fig. 1 of the drawing, 1 represents the upper of a shoe in flat condition before the heel end is closed and comprises a vamp 2 and toe or tip 3. The improvement, which constitutes the present invention, consists of a relatively narrow strip 4 of material extending around the edge of the leather vamp. This strip of material consists of a border of crimped or corrugated paper firmly secured to the edge of the leather by means of a con-

tinuous row of zig zag stitches 6, which pierce the edge of the leather and extend transversely across the area of the paper strip 4 to a point immediately beyond its outer edge. Here at this point a horizontal row of lock stitching 7 is provided which prevents the zig zag stitches 6 from becoming unraveled in case of a severance of the thread at either end. The row of lock stitching further provides protection along the edge of the paper strip 4 and furnishes a strong tangible edge to the marginal strip. The purpose of this strip of material is to afford an increased area coextensive with the leather provided with an edge which will be strong and capable of resisting effectively the strain to which it is normally subjected as the pull over clamps of the lasting machine stretch the upper over the last previous to the soling or welted process. It will be understood that the paper strip 4 is not intended to withstand the strain and wear but that it merely affords a suitable support of sufficient strength for holding the row of stitches 6 in place. The strip 4 need not be necessarily corrugated paper but any suitable thin flexible material may be substituted therefor, such as sized cloth or the like. It is not necessary that the strip 4 be glued or fastened to the leather by a separate step, as the inner edge of the stitches 6 piercing both the leather and the paper will suffice for this purpose. The advantage gained by having the strip 4 of paper in corrugated form is that it will more readily adjust itself to places of curvature in the formation of the shoe part or parts.

Referring to Fig. 2, it will be seen that after the strip 4 has been utilized in pulling over the vamp 2, when the shoe is of welted construction, and the upper has been secured by the usual inseam stitches 8 to the inner sole 9 and welt 10, the projecting portion of the strip 4 may be cut away or trimmed off in the usual manner, the leather portion being of such area that its edges require practically no trimming at all.

The stitches 6 may be provided with thread of any desired size or textile strength, and, as previously stated, the material of the strip 4 may also be varied to meet the special requirements for different kinds of stock.

Having thus described my invention what I claim is:—

1. A shoe upper comprising a body por-

- tion of leather and an edge portion co-extensive therewith, said edge portion comprising a relatively narrow strip of material, and a row of stitching extending back and forth from adjacent the outer edge of said leather to the outer edge of said strip for securing the strip to said leather.
2. A shoe upper comprising a body portion of leather, a marginal portion co-extensive therewith, said marginal portion comprising a strip of thin material, and a row of stitching secured to the outer edge of the leather and extending to and beyond the outer edge of said narrow strip.
- 15 3. A shoe upper comprising a body portion of leather, a marginal portion co-extensive therewith, said marginal portion comprising a narrow strip and a row of stitching extending from adjacent the edge of the leather out and around the outer edge of
- said narrow strip, said row of stitching being formed with a row of lock stitches at its outer edge.
4. A shoe upper comprising a body portion of leather, a marginal portion co-extensive therewith, said marginal portion comprising a narrow strip of corrugated material and a row of stitching extending through the outer marginal portion of the leather portion and the inner marginal portion of said strip at the inner edge of the row and around the outer marginal portion of said strip.
- 25 30 In testimony whereof, I affix my signature.

HIRAM HOLDEN.
